DESIGN FOR A LIPSTICK CASE

Maurice Chalom, New York, N. Y., assignor to Gloria Vanderbilt Corporation, New York, N. Y., a corporation of New York

Application October 8, 1946, Serial No. 133,820

Term of patent 14 years

(Cl. D86—10)

To all whom it may concern:

Be it known that I, Maurice Chalom, a citizen of France, residing at New York city, in the county of New York and State of New York, have invented a new, original, and ornamental Design for a Lipstick Case, of which the following is a specification, reference being had to the accompanying drawing, forming part thereof.

In the drawing:

Fig. 1 is a front perspective view of a lipstick case showing my new design; and
Fig. 2 is a rear perspective view.

I claim:

The ornamental design for a lipstick case, substantially as shown.

MAURICE CHALOM.
